UNITED STATES PATENT OFFICE.

WALTER S. MUMMERY, OF ELBA, MICHIGAN.

CREAMER.

SPECIFICATION forming part of Letters Patent No. 340,920, dated April 27, 1886.

Application filed August 15, 1885. Serial No. 174,500. (No model.)

To all whom it may concern:

Be it known that I, WALTER S. MUMMERY, of Elba, county of Lapeer, State of Michigan, have invented a new and useful Improvement 5 in Creamers; and I declare the following to be a full, clear, and exact description of the same, such as will enable others skilled in the art to which it pertains to make and use it, reference being had to the accompanying drawings, which form a part of this specification.

My invention relates to a novel construction and combination of devices in creamers, as hereinafter more fully specified, and more particularly pointed out in the claims.

15 In the drawings, Figure 1 is a vertical cross-section of a device embodying my invention. Fig. 2 is a longitudinal section; Fig. 3, a plan view with the cover removed. Fig. 4 is a separate view of one of the removable cans.

20 Heretofore as creamers have ordinarily been constructed in which cans are located in a tank, whereby said cans may be surrounded by cool water or ice for expeditiously concentrating the cream, the cans have not been readily removable; but it is evident that in order to keep them sweet and clean they need to be frequently scalded in a thorough manner, and for this purpose they should be made so as to be removed easily without the necessity of first emptying the tank, as has sometimes been the case, and of plugging up the orifices in the frame-work of the creamer and the tank through which the faucet of the can projects. Where the cans are not made re-

35 movable from the tank, the tank being cool by the presence of cold water or ice, it is evident that hot water poured into the cans in such location will readily become chilled, and in consequence the cans cannot be perfectly

40 scalded, and therefore not thoroughly cleaned, as the result of which a taint is likely to be imparted to the cream and the butter derived therefrom. Moreover, creameries are often situated at a distance from the house, in proximity to ice-houses, springs, or streams of running water, and unless the cans can be removed and carried to the kitchen loss of time and much inconvenience must be occasioned when it is time to scald them. My invention 45 is designed to overcome all these difficulties, and is carried out as follows:

A represents any suitable inclosing-case.

A' is a cover hinged or otherwise connected thereto. B is a tank engaged in the top of said case in any suitable manner, said tank 55 adapted to receive water or ice, as may be desired.

For supporting the tank I prefer to provide the case with strips a a' a'' x . The tank is made of suitable metal, its upper edges being 60 bent over so as to engage upon said strips. This is a convenient manner for engaging the tank in place in the upper part of the inclosing-case; but I would have it understood that I do not confine myself to any particular way 55 of securing the tank in place. The front strip, a , is preferably extended, so that the lower doors, A^2 , of the case may shut against the same to make a tighter union when the door is closed. Beneath the tank is a refrigerating-chamber, C, in which the cream-jar may be kept with any other desired commodities ordinarily set away in the refrigerator, the device answering both for a creamer and refrigerator. The refrigerating-chamber may be 70 provided with one or more shelves, C', suitably located therein.

I prefer to so locate the tank within the inclosing-case that an air-space shall be provided between the tank and the case upon the 8c different sides of the tank, as shown at b . This will greatly facilitate the cooling of the refrigerating-chamber, and will also serve to a considerable extent the purpose of a dead-air space in preserving the temperature within 85 the tank.

D represents a stationary can-holder, constructed with walls extending to or toward the top of the tank, and provided with a base, as shown. The tank may be provided with one 90 or more of these can-holders, as may be desired, the drawings showing but one, others, if employed, being constructed in a similar manner. Each of these holders is cut away at its lower front edge, with the adjacent portion of 95 the tank, to afford communication with the refrigerating-chamber.

E represents one of my improved cans removably located in said can-holder. Should it be desired, a series of these cans may be 100 provided located in a series of can-holders, arranged as before mentioned.

My improved cans are provided with any ordinary faucet, e , engaged with its lower front

end, and with an ordinary indicator-glass, e' , to show when the cream is approaching the faucet.

The bottom of the can-holders and cans are each inclined from the rear toward the front, as shown more particularly in Fig. 1, to facilitate the flow of the contents of the can through the faucet. The can-holders, being shaped in this manner, also permit the cooling fluid or ice coming in contact therewith beneath their base as well as about their sides. The can-holder and can are also preferably rounded at the bottom, so as to concentrate the flow of the contents of the can to the center, which also facilitates the cleansing of the can. I prefer, also, instead of leaving a corner at the lower rear point of the can, to secure therein a plate or strip, e^2 , which may be soldered in place, and which also facilitates the cleansing of the can. As so constructed, the can has no corners liable to be imperfectly cleaned.

The tank and can-holders are not only cut away at the lower front corner, as described, but I prefer that the cut shall extend rearwardly upon the front to give sufficient room for the faucet, the size of the faucet being such that the can to which it is attached may be readily lifted out of place in the can-holder and the faucet withdrawn through the cut-away portion of the tank and can-holder, the can-holder itself being soldered or otherwise securely engaged in the tank and projecting about the cut-away portion of the tank in such a manner that the contents of the tank are in no wise liable to escape therefrom when the can is lifted out of place, the can-holder and tank having a firm water-tight union with each other. This construction of a tank provided with a water-tight can-holder adapted to receive a can and cut away so as to afford communication from the interior of the can-holder through the tank is, so far as I am aware, an entirely novel feature, which I desire to cover broadly. The cut-away portion of the can-holder and tank also extends upwardly, so as to give a clear view of the indicator-glass in the can, as shown in Fig. 1 at e^3 .

E' represents a series of strengthening-strips, by which the can-holders may be more firmly engaged in the tank, although these, of course, are not essential to my invention, as these holders may be secured in place in any proper manner.

F represents an inlet-orifice extending through the inclosing-case and tank, adapted for the reception of water thereto, in which may be engaged a hose or other pipe, f , extending downward, so that the water entering will be discharged into the tank beneath the can-holders.

G represents a faucet extending through the inclosing-case and communicating with the interior of the tank, preferably at its base, for drawing off the water therefrom. This faucet may have any desired location; but it is extended to the exterior of the inclosing-case, so that water may be drawn from the

tank without opening the doors into the refrigerating-chamber.

g is an additional orifice in the base of the tank, which may be plugged up ordinarily, or which may be opened when occasion demands.

g' is a discharge-orifice toward the top of the tank, to prevent overflow.

H represents a cover, which I engage firmly upon the cover of the inclosing-case, adapted, when the cover is closed down in place, to rest over the top of the can and can-holder.

It is evident that more or less air may circulate between the can-holder and the can, and the animal heat in the can will rise and be condensed upon said cover, which is rounded, as shown, its ends being projected over the sides of the can-holder, so that the drip therefrom will flow into the tank. This constitutes a creamer, which may be readily cleansed and operated in the most efficient manner.

I am aware that it is not new to provide a milk-can with an inclined bottom, nor to arrange such can within a tank with the outlet of the can projecting through said tank. It is also old to provide a milk-can and its tank with transparent panels for observing the flow of the can contents. These, however, I do not broadly claim.

What I claim is—

1. In a creamer, the combination of a tank and a stationary can-holder therein, said tank and holder having coincident orifices, so that the interior of the holder communicates with the exterior of the tank, with a can arranged in the can-holder, and having an outlet extending through the orifices in the tank and can-holder, substantially as described.

2. In a creamer, the combination of a tank and a can-holder fitted water-tight therein, said tank and holder having coincident orifices, so that the interior of the holder communicates with the exterior of the tank, with a can arranged in the can-holder, and having at its lower portion a faucet extending through the orifices in the tank and holder, substantially as described.

3. In a creamer, the combination of a case, a tank supported therein, and a can-holder fitted water-tight in the tank, said tank and holder having orifices and a cut-away portion, e^3 , in their lower portions, so that the interior of the holder communicates with the exterior of the tank, with a can arranged in the holder, and having a faucet and an indicator-glass, both extending through the orifices in the holder and tank, substantially as described.

4. The combination of the tank having a horizontal bottom-wall and a can-holder having an inclined bottom wall, said holder and tank having coincident orifices, and fitted water-tight therearound, so that the interior of the holder communicates with the exterior of the tank, with a can arranged in the can-holder, and having an outlet extending through

the orifices in the holder and tank, substantially as described.

5. In a creamer, the combination of an inclosing case, a tank supported therein and separated therefrom by air-spaces, a chamber under the tank, a can-holder fitted water-tight in the tank, said holder and tank having coincident orifices in their lower portions, and a can arranged in said can-holder, and having

an outlet extending through the orifices in the holder and tank, substantially as described.

In testimony whereof I sign this specification in the presence of two witnesses.

WALTER S. MUMMERY.
